(57) **CLAIM**

The ornamental design for a remote control for boat, as shown and described.

DESCRIPTION

1. Remote control for boat
- 1.1 is a front elevation view of a remote control for boat showing our new design;
- 1.2 is a rear elevation view thereof;
- 1.3 is a top plan view thereof;
- 1.4 is a bottom plan view thereof;
- 1.5 is a right side elevation view thereof;
- 1.6 is a left side elevation view thereof; and
- 1.7 is a top, front, and left side perspective view thereof.
